(57) **CLAIM**

The ornamental design for a display panel with a transitional graphical user interface for a blast gauge, as shown and described.

DESCRIPTION

FIG. 1 is a front view of first embodiment of a display panel with a transitional graphical user interface for a blast gauge, showing my new design;

FIG. 2 is a second view thereof;

FIG. 3 is a third view thereof;

FIG. 4 is a fourth view thereof;

FIG. 5 is a fifth view thereof;

FIG. 6 is a sixth view thereof;

FIG. 7 is a seventh view thereof; and,

FIG. 8 is an eighth view thereof.

The appearance of the transitional image sequentially transitions between the images shown in FIGS. 1-8. The process or period in which one image transitions to another image forms no part of the claimed design.

The outermost broken line rectangle depicts a display panel that forms no part of the claimed design. The remaining broken lines illustrate portions of the graphical user interface that form no part of the claimed design.
